HENRY R. DILLS, OF TORONTO, ONTARIO, CANADA, ASSIGNOR OF THREE-FIFTHS TO
WILLIAM PUGSLEY, OF TORONTO, ONTARIO, CANADA.

REEL FOR CLOTHES, AWNINGS, AND THE LIKE.

1,184,835.

Specification of Letters Patent.

Patented May 30, 1916.

Application filed January 18, 1916. Serial No. 72,795.

To all whom it may concern:

Be it known that I, HENRY R. DILLS, of the city of Toronto, in the county of York, Province of Ontario, Canada, a subject of the King of Great Britain, have invented 5 certain new and useful Improvements in Reels for Clothes, Awnings, and the like, of which the following is a specification.

This invention relates to rotary reels such 10 as employed for drying clothes or supporting tents or awnings, and my object is to devise a reel which will better expose the clothes thereon to the action of the sun and wind than the ordinary reel, and which may 15 be filled with the clothes or stripped without the necessity of bodily raising or lowering the clothes supporting frame.

I attain my object by means of a construction which may be briefly described as follows. A rotary reel is provided adapted for 20 the support of the clothes, so supported and journaled that it may be rotated on an axis inclined to the vertical so that it may be faced more or less toward the sun. Preferably 25 the support of the reel is so arranged that the direction in which the reel is faced may be changed to suit the position of the sun during such times as the device is in use.

The whole is constructed in detail substantially as hereinafter more specifically described and as illustrated in the accompanying drawings in which—

Figure 1 is a side elevation of my improved reel; Fig. 2 a plan view of the standard; Fig. 3 a sectional detail of the upper part of the standard showing more particularly the bearing for the reel spindle; Fig. 4 a cross section of the standard taken above the pivots of the controlling links of the 40 spindle; Fig. 5 a side elevation partly broken away of part of the standard; and Fig. 6 a vertical section of parts of the same and its support.

In the drawings like numerals of reference indicate corresponding parts in the different figures.

1 is the support for the device, which is preferably a tube set in a concrete base embedded to a suitable depth in the ground. 50 On this support the standard of the device is carried, preferably in such a manner that the standard may be rotated. The standard comprises four angle bar members 2, which are suitably connected in spaced relationship

as shown. Preferably the angle bar members are arranged to form the four corners of a square, and are connected by a plurality of transverse plates, three preferably being employed. One of these forms a cap 3 for the standard, another 4 connects the lower ends of the members 2, and a third intermediate plate 5 forms a step bearing in which is received the upper end of the support 1, which also passes through a hole in the plate 4. The angle bar members may be connected to these plates by welding, riveting or in any other suitable manner.

If the plates 4 and 5 are arranged so that they turn freely on the support 1, it is preferable to provide the set screw 6, which is threaded through the plate 4 and engages the support to hold the standard from turning. Any suitable handle is provided for this screw.

The cap 3 has an opening therein for the passage of the reel spindle 7. At each side of the opening is formed an open bearing 8 adapted to receive the trunnions 9 formed on a collar suitably secured to the spindle 7. The spindle may thus rock freely on the cap 3, swinging between the spaced members of the standard.

The construction of the standard is of importance as the spindle, though supported directly in alignment with the axis of the standard, may swing freely to and from a vertical position, and may, if desired, be swung from either side of the central vertical position. The reel spindle 7 carries the reel, which in the main is of ordinary construction, comprising the arms 10 suitably connected with a tube 11 journaled on the reel spindle, which arms are braced from the upper end of the tube 11 by the diagonal braces 12 suitably secured to the upper end of said tube and preferably connected by clips 13 to the arms. On the arms the usual wires or cords will be strung to support the clothes.

A lock is provided to hold the reel from 100 rotating when such movement is undesirable. For this purpose I provide a lever 14 and a clip 15 secured to the reel spindle. This lever 14 has jaws formed thereon adapted to engage any one of the reel arms. 105 The jaws may be sufficiently tight to give a frictional grip and the pivot also be made sufficiently tight so that when the latch is

engaged with one of the arms 10 it will remain in engagement until manually disengaged.

Owing to the pivoting of the reel spindle 5 it is necessary to provide means for limiting the swinging movement and also for locking the spindle in vertical position when necessary. For this purpose I provide the following mechanism. Blocks 16 are riveted 10 or welded to the angle bar members 2. Each of these blocks is provided with a pivot 17 and on these pivots the links 18 are pivoted. These links at their other ends are pivoted at opposite sides of a sleeve 19 movable 15 freely longitudinally of the spindle 7. One of the pivots 17 is formed as a bolt, the nut 20 thereof being provided with a handle for convenient operation. By tightening up the nut 20 the adjacent link can be clamped 20 at any desired angle to the vertical so that the reel may be tilted to any desired angle. In practice, however, the link will probably be clamped at the limit of its swing, as the reel will mostly be employed at a predetermined angle.

As the sleeve 19 will move down the spindle as the latter is swung toward the vertical, the sleeve may be used to lock the spindle in vertical position. For this purpose I provide the plate 5 with a socket or otherwise suitably shape it for engagement with the lower end of the sleeve. To enable the sleeve to properly engage with the plate 5, it is necessary that it have some 30 small amount of movement longitudinally of the spindle while the latter remains in its vertical position. This is readily provided by giving each of the links 18 a limited amount of lost motion on one of its 35 pivots. Preferably the lost motion is provided at the pivots 17 by forming an elongated hole in each of the links. This enables the links to be pulled up sufficiently 40 when the spindle is in the vertical position to allow the sleeve 19 to lift above the socket in the plate 5, and thereafter to be dropped to engage therein. A handle 21 is 45 preferably secured to the sleeve for convenience in swinging the spindle 7. A box 22 to hold clothes pins is preferably 50 connected to the standard at one side.

The advantage of this arrangement of the reel as described is that with the reel set at an angle, the clothes receive the full 55 benefit of the sun's rays and the wind, as the surfaces of the clothes in the inner wires of the reel are much better exposed to the sun's rays than they could possibly be with the reel journaled to rotate in a horizontal plane. The lower side of the reel 60 is also at a convenient height for the clothes to be hung on the lowest side of the reel. As soon as the side which is lowest at the 65 beginning of operations has been filled up with clothes, the reel is rotated to bring

another portion of the reel to the lowest position. The weight of the clothes already hung on the reel tends to rotate the reel to bring this section lowest, but the catch 14 provides means for locking the reel in position until it is necessary to turn it to a fresh position.

The general construction of the device, it will be seen, is simple, strong and convenient.

What I claim as my invention is:—

1. The combination of a suitably supported standard; a reel spindle pivoted intermediate of its ends on the upper part of said standard; a reel carried by the upper end of said spindle; a sleeve slidable on the spindle; and a link pivotally connected at one end to said sleeve and at the other end to the standard. 70

2. The combination of a suitably supported standard; a reel spindle pivoted intermediate of its ends on the upper part of said standard; a reel carried by the upper end of said spindle; a sleeve slidable on the spindle; a link pivotally connected at one end to said sleeve and at the other end to the standard; and means for clamping said link at its pivot to hold it at different angles to said standard. 80

3. The combination of a suitably supported standard; a reel spindle pivoted intermediate of its ends on the upper part of said standard; a reel carried by the upper end of said spindle; a sleeve slidable on the spindle; a link pivotally connected at one end to said sleeve and at the other end to the standard; and a socket connected to the standard in which the lower end of the sleeve may engage when the spindle is in a vertical position, lost motion being provided at one of the pivots of the link to enable the latter to be lowered and raised sufficiently to enable it to be engaged with and disengaged from said socket. 90

4. The combination of a standard comprising four angle bar members and a plurality of plates to which said members are connected in spaced relationship, the upper plate having an opening through it and being provided with an open bearing at each side of the opening; a reel spindle passing through the opening in said upper plate; trunnions on said spindle resting in said bearings; and a reel carried by the upper end of the spindle. 110

5. The combination of a standard comprising spaced longitudinal members between which a reel spindle may swing; cross members connecting said longitudinal members one of which is located substantially at the top of the standard; a reel spindle pivotally connected to swing on said upper member; a link pivoted between said longitudinal members; a sleeve slidable on the reel spindle to which the other end of said 120

link is pivoted; means for locking the spindle in the vertical position; and a reel carried at the upper end of the spindle.

6. The combination of a standard comprising spaced longitudinal members between which a reel spindle may swing; cross members connecting said longitudinal members one of which is located substantially at the top of the standard; a reel spindle 10 pivotally connected to swing on said upper member; blocks secured to the inner sides

of said spaced longitudinal members; links pivoted on said blocks; and a sleeve slidable on said reel spindle to which the other ends of said links are pivoted.

15

Signed at Toronto, Canada, this 12th day of January, 1916, in the presence of the two undersigned witnesses.
